UNITED STATES PATENT OFFICE.

PHILIP FLORENZ AND JOSEPH MAGLUILO, OF OZONE PARK, LONG ISLAND, NEW YORK.

DESIGN FOR A BIRDCAGE.

Application filed May 22, 1926. Serial No. 17,816. Term of patent 7 years.

To all whom it may concern:

Be it known that we, PHILIP FLORENZ and JOSEPH MAGLUILO, citizens of the United States, residing at Ozone Park, Long Island, New York, have invented a new, original, and ornamental Design for a Birdcage, of which the following is a specification, reference being had to the accompanying drawing, forming part thereof.

The figure is a perspective view of a bird cage, showing our new design.

We claim:

The ornamental design for a birdcage, as shown.

PHILIP FLORENZ.
JOSEPH MAGLUILO.
